INVENTOR.

Henry Cave,
BY
Arthur B. Jenkins,
ATTORNEY.

UNITED STATES PATENT OFFICE.

HENRY CAVE, OF HARTFORD, CONNECTICUT, ASSIGNOR TO THE FULLER BRUSH COMPANY, OF HARTFORD, CONNECTICUT, A CORPORATION OF CONNECTICUT.

COLLAPSIBLE RECEPTACLE.

Application filed December 17, 1923. Serial No. 681,082.

My invention relates more especially to the class of receptacles arranged to be supported in elevated positions and from which the contents, as water, will flow by gravity for various uses, as for bath purposes, and an object of my invention, among others, is to provide, in a device of this class, that may be folded into compact form, means for enabling the valve in the stop-cock to be readily manipulated; and a further object of the invention is to provide means that, while permitting ready manipulation of the valve of the stopcock, shall at the same time permit such stop-cock to function completely and shall also permit all of the advantages with respect to the collapsibility of the structure to be attained.

One form of device embodying my invention and in the construction and use of which the objects herein set out, as well as others, may be attained, is illustrated in the accompanying drawings, in which—

Figure 1 is a view in side elevation of a collapsible receptacle embodying my invention.

Figure 2 is a detail view, scale enlarged, in vertical central section through my improved receptacle.

Figure 3 is a bottom view of the same.

Figure 4 is a view showing the receptacle in its collapsed condition, the scale being the same as that of Figure 1.

In order to provide for a flow of water, as for bath or other purposes, especially in rural districts where water supplies are deficient, it has heretofore been proposed to produce a receptacle or bucket that may be of water therefrom, as through a tube that placed in an elevated position to cause flow may be secured to a stop-cock in the bottom of the receptacle or bucket. In order to provide for ready storage of such receptacle it has been constructed of canvas or similar flexible material attached to a frame, usually of metal, provided with means to permit the receptacle to be collapsed.

The bottoms of such receptacles have been composed of canvas or other flexible material and the stop-cocks have been secured to such bottoms, but a disadvantage has been found to exist in such structures from the fact that the stopcock being supported by the bottom of flexible material is very unstable, as such support, and difficulty has, therefore, been encountered in an effort to

turn the valve of the stop-cock, and especially when such valve is somewhat tight, as is usually the case in order to prevent leaking.

I have provided means for overcoming such objections, such means being shown in the drawings herein in which the numeral 5 indicates a receptacle that is composed of canvas or other flexible material, such receptacle having a bottom 6 composed of the same material. This receptacle also comprises a flange 7 extending around the bottom edge, and a stiffening ring 8, as of metal, is commonly employed at the bottom, as well as the top, for stiffening the bottom and top edges. A stop-cock 9, having a thumb piece 10 secured in any ordinary manner to a valve located within the body of the stopcock, is attached to the bottom 6.

In order to overcome the objections heretofore existing by reason of the flexible mounting of the stop-cock I provide a support 11 projecting from the ring 8, this support being of any suitable rigid material and being secured to the stop-cock in any suitable manner. As herein shown an opening is formed through the support, through which opening the inner end of the stop-cock extends, and the parts may be secured in position in any suitable manner, as by means of a nut 12 fitting the screw-threaded end of the stop-cock, and a washer 13 may be employed, if necessary, located between the support and the bottom 6 of the receptacle. This support imparts sufficient rigidity to the stopcock to enable the thumb piece 10 to be readily turned.

In order that the receptacle may be placed in its collapsed condition and as illustrated in Figure 4, and in order that in such condition the stop-cock shall not project below the bottom of the collapsed structure, and further, in order that the bottom of the receptacle may be permitted its customary sag to enable the contents to readily flow out of the stop-cock I provide a flexible connection for the support 11, altho it will be understood that such flexible connection is not absolutely essential to the presence of my invention.

As one means for obtaining this flexible connection I provide a bracket 14 that may be secured to the ring 8 in any suitable manner, as by riveting, and a hinge 15 is provided for connecting the support to the

110

bracket, and as clearly shown in Figure 2 of the drawings.

From this construction it will be seen that while the stop-cock is rigidly supported to resist the forces necessary to turn the thumb piece of the valve, yet the support may yield in certain directions to enable the full benefits of the flexibility of the bottom to be obtained, as to the outflow of liquid, and this flexibility of the bottom also being made use of when the receptacle is collapsed to permit the stop-cock to be located within the collapsed structure, and, therefore, not to project beyond the boundaries of such collapsed structure.

A further advantage of the support for the stop cock herein described resides in that feature whereby the stop cock may be located with its lower end above the plane of the bottom of the receptacle, or at least not below that plane. If the receptacle be filled or partially filled with water or liquid it may be set down and the lower end of the faucet will be forced upwardly so that it will not interfere with the stable support of the bucket resting upon its bottom edge.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim—

1. A receptacle having a bottom composed of flexible material, a stop cock secured to

said bottom for the outflow of liquid from the receptacle, said stop cock extending below the plane of the bottom of the receptacle when the latter is extended, and a support of rigid material flexibly mounted and connected with the stop cock for support thereof, said support being arranged to support the stop cock with its outer end not lower than the plane of the bottom of the receptacle whereby the latter may rest upon its bottom edge without interference by said stop cock.

2. A receptacle having a bottom composed of flexible material, a stop-cock secured to said bottom for the outflow of liquid from the receptacle, and a support of rigid material connected with the stop-cock for support thereof, said support also being flexibly connected with a rigid portion of the receptacle.

3. A collapsible receptacle having a bottom of flexible material, a stop-cock secured to said bottom, a stiffening band extending around the bottom of the receptacle, a support connected with said band and attached to said stop-cock for support of the latter, and a flexible connection between said support and said band.

4. A receptacle having a bottom of flexible material, a stiffening member comprised in said receptacle, a stop-cock secured to said bottom, a support attached to said stop-cock, and a hinged connection between said support and said stiffening member.

5. A receptacle having a bottom of flexible material, a stiffening band extending around the bottom of the receptacle, a bracket secured to said band, a support hinged to said bracket, and a stop-cock secured to said bottom and also attached to said support.

HENRY CAVE.
